Application Ser. No. 709,080 (now U.S. Pat. No. 3,433,705) was filed, prosecuted, issued and assigned to the U.S. Government by the Applicant/Inventor's Representative in this case for the benefit of the Government, and under federally sponsored research as a Registered patent attorney under Registration No. 19,240.

The patent or application file contains at least one drawing executed in color, as shown in the attached three sets of color drawings. Copies of this patent or patent application publication with color drawing(s) will be provided by the Office upon request and payment of the necessary fee.

The FIGURE is a front view of a portion of a display screen with an icon showing my new design. The broken line showing of a portion of a display screen forms no part of the claimed design.

This invention provides a novel unobvious and non-functional design of an article of manufacture identified as a portion of a display screen with an icon showing the entity of my new design as a portion of a display screen with an icon, which is described, claimed and shown with a red scan code submitted originally to which the application has been reverted. The icon is a sign having symbols, images and representations in a particular style with black and red design elements, including the word "Cosential" in a motto as part of the design under 35 U.S.C. 171 and MPEP 1509.
